(57) **CLAIM**

The ornamental design for a phone case, as shown and described.

DESCRIPTION

FIG. 1 is a front perspective view of a phone case showing my new design.

FIG. 2 is a partial enlarged view of portion 2 in FIG. 1.

FIG. 3 is a partial enlarged view of portion 3 in FIG. 1.

FIG. 4 is a partial enlarged view of portion 4 in FIG. 1.

FIG. 5 is a rear right perspective view thereof.

FIG. 6 is a rear left perspective view thereof.

FIG. 7 is a front view thereof.

FIG. 8 is a rear view thereof.

FIG. 9 is a left side view thereof.

FIG. 10 is a right side view thereof.

FIG. 11 is a top view thereof; and,

FIG. 12 is a bottom view thereof.

The broken line portions of the phone case represent features that form no part of the claimed design. The broken line circles and lead lines that appear in FIGS. 1-4 are included for the purpose of delineating the bounds the enlarged views and form no part of the claimed design.

1 Claim, 12 Drawing Sheets(56)
